UNITED STATES PATENT OFFICE.

PERCY Q. WILLIAMS, OF CINCINNATI, OHIO.

BOTTLE-POSITIONING DEVICE.

Application filed July 19, 1923. Serial No. 652,491.

To all whom it may concern:

Be it known that I, PERCY Q. WILLIAMS, a citizen of the United States of America, and a resident of Cincinnati, in the county 5 of Hamilton and State of Ohio, have invented a new and useful Improvement in a Bottle-Positioning Device, of which the following is a specification.

In the manufacture of glassware it is 10 often desirable to have the articles definitely positioned after the molding operation has been performed.

An object of my invention is to provide a device by means of which bottles or other 15 articles of glass may be definitely positioned as they are conveyed from the bottle machine.

Another object is to provide a device of 20 this type that will be simple and efficient in operation.

These and other objects are attained by the means described herein and disclosed in the accompanying drawings in which;

Fig. 1 is an end elevational view of a 25 device of my invention.

Fig. 2 is a fragmental side elevation of Fig. 1.

Fig. 3 is a fragmental plan view showing 30 certain features of my device.

Fig. 4 is a cross section view taken on line 4—4 of Fig. 3.

Fig. 5 is a cross sectional view on line 5—5 of Fig. 4.

Fig. 6 is a cross sectional view taken on 35 line 6—6 of Fig. 3.

My invention is for use primarily in the manufacture of rectangular or panel bottles. When this type of bottle comes from the bottle making machine and the glass is still 40 hot and soft, the large side of the bottle will sag under its own weight if allowed to lie flat. The remedy for this is to place the bottle with one of the narrow sides down. This is accomplished automatically by the 45 use of a device of my invention. The bottles leave the bottle making machine 7 and are discharged neck end foremost onto an inclined chute 8 of my device. The device consists of a positioning means in conjunction with a conveyer. The conveyer 9 may be of any type common in the art and has an endless belt 10 actuated in the usual manner. Mounted on the conveyer frame are two uprights 11 and 12 substantially U-shaped in form, each having one of its arms secured on opposite sides of the conveyer

frame. The arms 11 and 12 are spaced on opposite sides of the discharge end 7 of the bottle machine. A chute 8 is pivotally mounted between the pairs of uprights 11 60 and 12 on the side adjacent the bottle making machine. A chute 13 is mounted in a like manner on the opposite side of the conveyer. The mountings are adjustable vertically horizontally and pivotally as shown 65 in Figs. 4 and 5. The adjustments being the same, a description of one will serve for all.

The upright 12 has formed in it a longitudinal dovetailed groove 14 in which the 70 dovetailed rib 15 of the block 16 engages. The block 16 has a dovetailed groove 17 extending transversely to and on the opposite side from the rib 15 and a rib 19 on bracket 18 which fits into the groove 17. Each of 75 the dovetailed adjustments may be secured against movement by means of suitable set screws 20 or any other desirable means. Each of the brackets 18 carries a stud or pivot 21 which projects thru the side of the 80 chutes 8 and 13 thereby providing pivotal adjustment of the angle of incline of said chutes. Suitable set screws 22 provide a locking means for such adjustment of the 85 chutes. Thus it will be seen that the chutes are adjustable laterally of the conveyer, as well as for elevation and angle of incline in relation to the conveyer belt 10.

The particular feature of the invention consists of the positioning apparatus carried 90 by the chute 13. This comprises a diagonal deflector block 23 longitudinally and slidably adjustable within the chute 13 by means of an adjustment screw 24 provided with a crank 25 and engaging a threaded 95 block 26 on the rear end of chute 13, the end of the screw being swiveled to a projection 29 on the rear of the deflector 23 which projects thru a suitable slot 27 in the bottom of chute 13. 100

In operation the chute 8 is positioned and secured at proper angle so that the bottles 28 as they are discharged from the bottle making machine 7 are carried by gravity down the chute 8. The chute 13 is positioned with its lower end spaced from the lower end of chute 8 at a distance slightly greater than the smaller dimension of the bottle to be positioned. The bottle having been carried neck end foremost down the 110 chute 8 is projected across the gap onto the upwardly inclined surface of the chute 13,

where it encounters the diagonal face of the deflector block 23 which deflects or swings the bottle sideward whereupon the force of gravity again carries the bottle 5 down toward the conveyor belt 10. The gap between the lower ends of the chutes 8 and 13 being smaller than the major dimensions of the bottle, will therefore cause the bottle to turn and drop onto the belt 10 10 resting on one of the narrow sides, the neck of the bottle always in a given direction. Proper adjustment of the angles of inclination of the chutes and spacing of the ends thereof will result in accommodating various 15 shapes and sizes of bottles including round as well as panel bottles.

What I claim is:

1. In a device of the class described, the combination of a downwardly inclined chute 20 for receiving and directing bottles neck end foremost, a second upwardly inclined chute for receiving at its lowermost end the bottles as they are discharged from the lower end of the first mentioned chute and means carried by the second chute for deflecting the bottles to a position transversely of the chutes.

2. In positioning device for bottles the combination with a conveyor of an inclined 30 chute upwardly of which bottles supported on their sides are moved neck end foremost and means carried by the chute for turning the bottles at substantially right angles to the initial direction of travel thereof the chute delivering the bottles on their sides to the conveyor.

3. In a positioning device for bottles, comprising a downwardly inclined chute for receiving bottles neck end foremost, an upwardly inclined chute having its lower end spaced from the lowermost end of the first mentioned chute, the chutes being in substantial longitudinal alignment, and means 40 on the second mentioned chute for turning the bottles transversely of the line of travel over the chutes.

4. In a positioning device for panel bottles having pairs of wide and narrow sides, the combination with a belt type conveyor, of a downwardly inclined chute over which bottles slide neck end foremost, an upwardly inclined chute having its lower end spaced from the lower end of the first mentioned chute at a distance slightly greater than the narrow dimension of the bottle, and to which lower end the bottles are directed by the first mentioned chute, means for turning the bottles on the second chute to a position 50 at an angle to their original line of travel and from which position the bottle may pass, under the influence of gravity, upon one of its narrow sides between the spaced ends of the chutes on to the conveyor.

5. In a gravity actuated positioning device for panel bottles having wide and narrow sides, the combination with a conveyor of means comprising a pair of oppositely inclined chutes spaced at their lower ends at a distance slightly greater than the narrow dimension of the bottle and a deflector in one of said chutes for turning the bottles transversely of the chutes and discharging them upon one of the narrow sides upon the conveyor.

6. In a positioning device for panel bottles the combination with a conveyor, of adjustable oppositely inclined chutes having their lower ends spaced at unequal distances above the conveyor and a diagonal adjustable deflector in the lowermost chute.

7. In a positioning device for bottles having wide and narrow sides, the combination with a belt type conveyor of a downwardly inclined chute over which bottles slide neck end foremost, an upwardly inclined chute having its lower end spaced from the lower end of the first mentioned chute at a distance intermediate the width of the wide and narrow sides of the bottles, and to which lower end the bottles are directed by the first mentioned chute, means for turning the bottles on the second chute to a position at an angle to their original line of travel and from which position the bottles may pass, under the influence of gravity, upon one of the narrow sides, between the spaced ends of the chutes on to the conveyor.

8. In a positioning device for panel bottles, the combination with a conveyor, of oppositely inclined chutes having their lower ends spaced at unequal distances above the conveyor and a diagonally disposed deflector in the lowermost chute.

9. In a positioning device for bottles the combination with a conveyor, of an inclined chute for supporting bottles on their sides and down which chute bottles move endwise, a second chute mounted above the conveyor 100 for receiving bottles endwise from the first chute, and means carried by the second chute for turning the bottles transversely of the chutes the second chute delivering said bottles upon their sides onto the conveyor.

10. In positioning device for panel bottles having wide and narrow sides, the combination with a conveyor, a chute down which bottles slide endwise, a second chute for receiving bottles from the first chute, and means in the second chute for turning and delivering said bottles upon one of their narrow sides onto the conveyor.

In testimony whereof, I have hereunto subscribed my name this 16th day of July, 125 1923.

PERCY Q. WILLIAMS.
